ILLUMINATED CARD HOLDER

Leo J. Buhr, Lake Zurich, Ill.

Application January 26, 1937, Serial No. 122,444

2 Claims. (Cl. 40—132)

This invention relates to illuminated card holders of a type generally similar to that constituting the subject matter of my U. S. Patent Number 1,943,719, upon which the present device constitutes an improvement.

An important object of the present invention is to provide, in a manner as hereinafter set forth, a holder of the aforementioned character embodying a removable indicia bearing card, together with novel means for securing said card in position against unauthorized removal.

Other objects of the invention are to provide an illuminated card holder of the character described which will be comparatively simple in construction, strong, durable, highly efficient and reliable in use, compact, light in weight, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation, showing an improved illuminated card holder embodying the present invention mounted in position in the lower left hand corner portion of an automobile windshield.

Figure 2 is a view in front elevation of the invention.

Figure 3 is a view in vertical section through the invention, taken substantially on the line 3—3 of Fig. 2.

Figure 4 is a top plan view.

Figure 5 is a view in front elevation and partially in vertical section, the card and the container therefor being omitted.

Referring now to the drawings in detail, it will be seen that the embodiment of the invention which has been illustrated comprises a casing 1 of suitable metal, said casing being open at its front and further being substantially of the shape shown to advantage in Figs. 3 and 4 of the drawings. Mounted vertically in the lower portion of the casing 1 is a socket 2 for the reception of an incandescent lamp 3. The reference numeral 4 designates a reflector in the casing 1. Brackets 5 project from one side and the lower end of the casing 1 for firmly securing said casing in position in the lower left hand corner portion of the windshield 6 of an automobile 7. Of course the device is mounted in back of the windshield 6.

55 A transverse opening or slot 8 is provided in

the upper portion of the casing 1 and aligned with said slot in the open front portion of said casing 1 are substantially channel shaped metallic guides 9. The guides 9 are open at their upper ends for the reception of a removable container in the form of a transparent envelope 10 which is open at its upper end. The reference numeral 11 designates a transparent or translucent card in the envelope 10 which, as best seen in Fig. 2 of the drawings, may have printed thereon any 10 desired indicia, as at 12. Projecting from the open upper end of the envelope 10 and integral with said envelope is a tab 13 which is adapted to extend through the slot 8 in the casing 1. A bar 14 extends transversely across the open front of the casing 1 at the top thereof and constitutes the forward wall of the slot 8. Mounted on the bar 14 and on the outer flanges of the substantially channel shaped guides 9 is a pad 15 of suitable material, such as felt.

20 Mounted in the upper portion of the container 1 is a lock 16 which is operable by a key 17, a hole 18 being provided in the casing for said key. Fixed on the bolt 19 of the lock 16 is a closure 25 plate 20 for the slot 18. The closure plate 20 has formed therein a notch or recess 21 which accommodates the tab 13.

25 It is thought that the operation of the improved device will be readily apparent from a consideration of the foregoing. With the card 30 11 placed therein, the envelope 10 is inserted in the substantially channel shaped guides 9 through the slot 8 in the top of the casing 1. The lock 19 is then actuated through the medium of the key 17 for shifting the closure 20 35 to operative position relative to the slot 8, as seen in Fig. 3 of the drawings, thereby preventing unauthorized removal of the card, the notch or recess 21 accommodating the tab 13. When the incandescent lamp 3 is energized the indicia 12 on the transparent or translucent card 11 will be illuminated through the transparent envelope 10. Of course, the open front of the device is held against the glass of the windshield of the vehicle by the attaching brackets 5. When it 40 is desired to remove the card the lock 16 is actuated in a manner to retract the closure plate 20 45 thereby permitting the envelope 10, with the card therein, to be withdrawn through the slot 8 through the medium of the tab 13.

50 It is believed that the many advantages of an illuminated card holder constructed in accordance with the present invention will be readily understood and although a preferred embodiment of the device is as illustrated and described, 55

it is to be understood that changes in the details of construction and in the combination and arrangement of parts may be resorted to which will fall within the scope of the invention as claimed.

5 5 What is claimed is:—

1. A holder of the class described comprising a casing open at its front, said casing having a slot in its front portion, substantially channel shaped guides mounted in the front portion of 10 the casing in alignment with the slot for the reception of a card, a lock mounted in the casing and operable by a key, said lock including a bolt, a plate fixed on the bolt and adapted to close the slot, and a lamp mounted in the casing for 15 illuminating the card.

15 2. A holder of the class described comprising,

in combination, a casing open at its front and having a slot in its front portion, substantially channel shaped guides mounted in the front portion of the casing and aligned with the slot, a transparent envelope, for the reception of a card, insertable in the guides through the slots, said envelope including a tab adapted to project through the slot when the envelope is in position in the guides, a key operated lock mounted in the casing and including a bolt, a plate fixed 10 on said bolt and adapted to close the slot, said plate having a recess therein accommodating the tab, and a lamp mounted in the casing for illuminating the card.
